Primary Examiner — Cathy Anne MacCormac(74) *Attorney, Agent, or Firm* — Brinks Gilson & Lione(57) **CLAIM**

We claim the ornamental design for an outdoor animal enclosure, as shown and described.

DESCRIPTION

FIG. 1 is a front perspective view of an outdoor animal enclosure.

FIG. 2 is a rear elevation view of the outdoor animal enclosure of FIG. 1.

FIG. 3 is a front elevation view of the outdoor animal enclosure of FIG. 1.

FIG. 4 is a right side elevation view of the outdoor animal enclosure of FIG. 1, the left side elevation view is a mirror image of the right side view shown.

FIG. 5 is a top plan view of the outdoor animal enclosure of FIG. 1; and,

FIG. 6 is a bottom plan view of the outdoor animal enclosure of FIG. 1.

The broken lines depict environmental subject matter and form no part of the claimed design.
